Primary Examiner — Mary Ann Calabrese(74) *Attorney, Agent, or Firm* — Banner & Witcoff, Ltd.(57) **CLAIM**

The ornamental design for a platform, as shown and described.

DESCRIPTION

FIG. 1 is a top, front, left perspective view of a platform showing my new design;
 FIG. 2 is a top view thereof;
 FIG. 3 is a front view thereof;
 FIG. 4 is a rear view thereof;
 FIG. 5 is a left side view thereof;
 FIG. 6 is a right side view thereof;
 FIG. 7 is a bottom view thereof; and,
 FIG. 8 is a bottom, front, left perspective view thereof.
 The broken lines depicting the remainder of the platform show features that form no part of the claimed design.

1 Claim, 8 Drawing Sheets(56)
